UNITED STATES PATENT OFFICE.

DANIEL RUBEN IVETT, OF WHITEBEAR, MINNESOTA.

CONDENSING-LOCOMOTIVE.

SPECIFICATION forming part of Letters Patent No. 730,020, dated June 2, 1903.

Application filed October 31, 1902. Serial No. 129,575. (No model.)

To all whom it may concern:

Be it known that I, DANIEL RUBEN IVETT, a citizen of the United States, and a resident of Whitebear, in the county of Ramsey and State of Minnesota, have invented a new and Improved Condensing-Locomotive, of which the following is a full, clear, and exact description.

My invention relates to locomotives with condensing-engines, although the salient features of the invention may be utilized in stationary and traction engines.

In my present invention the exhaust-steam from the valve-chests is subjected to the action of jets of cold water injected under pressure by pumps supplied with cold water from the tender or other source. The partially-heated water is mechanically forced back to the tender by another set of pumps, while any spent steam which may remain after condensation is subjected to compression and is forced under pressure back into the steam-space of the boiler.

A locomotive equipped with a condensing-engine of my invention is believed to be capable of operation in a way to economize the consumption of fuel and to minimize the cost of repairs, owing to the fact that it will not be necessary to maintain intense heat in the fire-box, due to the forced draft, which causes the products of combustion to circulate so rapidly as to result in deterioration of various parts of the structure. The several mechanisms which are embodied in the improved engine are disposed in a compact manner, each of these parts being simple in construction and organized in relation to other parts to secure efficiency in the operation of the structure as a whole.

Further objects and advantages of the invention will appear in the course of the subjoined description, and the novelty will be defined by the annexed claims.

Reference is to be had to the accompanying drawings, forming a part of this specification, in which similar characters of reference indicate corresponding parts in all the figures.

Figure 1 is a side elevation of a locomotive equipped with condensing-engines of my invention. Fig. 2 is a vertical longitudinal section, on an enlarged scale, through the front part of the condensing-engine and locomotive-

boiler, the plane of the section being indicated by the irregular dotted line 2 2 of Fig. 4 looking in the direction of the arrow. Fig. 55 3 is a vertical transverse section on the same scale as Fig. 2, taken in the plane of the dotted line 3 3 of Fig. 2. Fig. 4 is another vertical transverse section taken in the plane of the dotted line 4 4 of Fig. 2 looking in the 60 direction of the arrow. Fig. 5 is an enlarged detail sectional elevation through certain parts of the running-gear and illustrating the pump mechanisms and various other parts contemplated by this invention. Fig. 65 6 is a sectional elevation through an engine-cylinder and its valve-chest, the plane of the section being indicated by the dotted line 6 6 of Fig. 4; and Fig. 7 is a detail section in the plane of the dotted line 7 7 of Fig. 4, illustrating one of the compressing-pumps.

A designates the boiler of a locomotive, B B' the axles having the drive-wheels B², and C a part of the framework, these parts being of the ordinary or any preferred construction. 75

The saddle of the locomotive is cast in two halves or members, (indicated at D D' in Figs. 1, 3, and 4.) The saddle members have straight inner faces disposed in abutting relation, as shown by Figs. 3 and 4, and united 80 in any suitable way—as, for example, by flanging the parts and bolting them together. The upper side of the saddle formed by the two members is curved to provide a seat on which rests the front end of the boiler A, and this saddle on its under side is fashioned to fit upon the frame C, whereby the saddle as an entirety is adapted to be united to the front part of the boiler and to the running-frame in order to join the parts substantially 90 together.

E E' designate the piston-cylinders of the engines, which cylinders are provided in the members D D' of the saddle. The cylinders are made in the saddle members by boring 95 the latter to the proper diameter, and the ends of these cylinders are closed by heads, (indicated at e in Fig. 6.) In each cylinder operates a piston-head F, having a suitable packing and attached to a piston-rod f, the front end of which rod works in a closed tubular cap f', which is fixed to the front head e, while the rear part of said piston-rod plays in a stuffing-box f², provided on the rear head 100.

of the cylinder. As is usual, the piston-rod is connected with a cross-head f^3 , which is slideable in a guideway, and from this cross-head extends a pitman f^4 , having a crank connection with one of the drive-wheels B^2 . (See Fig. 1.)

- G G' designate the valve-chests, which are provided in the members of the saddle by boring the latter to the proper diameter, said valve-chests being disposed above the piston-cylinders and connected therewith through the steam-passages g g' . The ends of each valve-chest are closed by suitable heads g^2 , and the front head is provided with a tubular closed cap g^3 , while the rear head has a stuffing-box g^4 . (See Fig. 6.) In each valve-chest operates a piston-valve, consisting of the piston-rod H and the heads h h' , the front end of said piston-valve rod being arranged to play in the cap g^3 , while the rear portion of said valve-rod travels in the stuffing-box g^4 . Live steam is conveyed to the steam-chests in the members of the saddle by a pipe I , which is carried through the front tube-sheet a of the boiler into the smoke-box J , from which rises the smoke-stack J' . The pipe I is provided with two branches i , which are led downwardly along the inner sides of the smoke-box J and connect with pipes i' , leading to the inlet-ports G^2 of the valve-chests, one of said ports G^2 being provided at the middle portion of each valve-chest, so as to supply steam between the piston-heads h h' of the piston-valves. Said piston-valves are connected operatively with the rocker-arms G^3 by extending the piston-valve rods H rearwardly for suitable distances, and with these rocker-arms are associated the usual link-motions K . (See Figs. 1 and 5.)
- Each valve-chest G G' is provided with exhaust-ports m m' , situated near the ends of the chest and on opposite sides of the inlet-port G^2 , and these exhaust-ports communicate with passages M M' . (Indicated by dotted lines in Figs. 2 and 4 and by full lines in Fig. 3.) The exhaust-passages are provided in the saddle members D D' to extend downwardly and inwardly from the valve-chests to the condensing-chambers 5 6 , the latter being provided in the saddle members by boring the latter to the proper diameter. These condensing-chambers are formed in the saddle members within the vertical planes of the piston-cylinders and the valve-chests, although the two condensing-chambers are separate one from the other.
- The members of the saddle are furthermore provided with the cylinders 7 8 of the compressing-pumps, the same being formed in the upper parts of the saddle members by boring the latter to the proper diameter, said cylinder 7 8 lying above the valve-chests and the condensing-chambers and within the vertical planes of the piston-cylinders and the valve-chests. (See Figs. 3 and 4.) The cylinder of each compressing-pump is closed at its ends by the heads 9 10 , as shown by Fig.

7, and the front head is provided with a tubular closed cap 11 , while the rear end has a stuffing-box 12 , in which is adapted to play a piston-rod 13 , which carries a piston-head 14 . The compressing-pumps are operatively connected with the condensing-chambers, and the piston-heads of said pumps are reciprocated by suitable pump-driving mechanism, all as will hereinafter appear.

I will now proceed to describe the construction of the parts employed in the condensing-chambers, and as these chambers and their parts are similar in construction a description of one will answer equally for the other. The chamber 5 or 6 is provided with a baffle 15 , which is preferably made an integral part of one saddle member and has the pointed shape shown more clearly by Fig. 4. This baffle depends from the saddle member and the upper part of the condensing-chamber, but the lower pointed end of this baffle terminates a suitable distance above the bottom of the condensing-chamber and a cavity or subchamber 16 , which is provided in the saddle member below the condensing-chamber and in communication therewith. In the end portions of the condensing-chamber are placed short cylindrical shells 17 18 , which are made integral with heads 19 , that close the end portions of each condensing-chamber, and these cylindrical shells are provided with external spiral flanges 20 , having one or more convolutions and fit snugly within the condensing-chamber, so as to provide spiral circulating-passages 21 . (See Fig. 3.)

Between the shells and the spiral flanges thereof are disposed condensing-nozzles 22 23 , each of which is provided with an external flange 24 to engage with an inwardly-projecting flange $24'$, that is disposed within the condensing-chamber, and these nozzles are clamped against the flanges of the condensing-chamber by the shells 17 18 on the heads 19 , that are bolted to the saddle member. The condensing-nozzles are disposed on opposite sides of the central baffle 15 , and said nozzles are disposed to discharge toward each other and toward the baffle, as clearly shown by Fig. 2. Each nozzle may be of conical tapering form; but, as shown by said Fig. 2, I prefer to provide the interior part of the nozzle with a series of steps or shoulders 25 , each successively smaller than the preceding step, and the inner end of said nozzle is provided with a contracted jet-orifice 26 .

Within each cylindrical shell 17 or 18 is provided a spray-plate 27 , the same being secured in any suitable way at the inner portion of the shell and next to the large end of the condensing-nozzle, and this plate is provided with a plurality of jet-openings 28 , the same arranged around the edge portion of the plate and next to the inner surface of the shell. The spray-plate has an inclined baffle 29 , which extends toward the head 19 of the condensing-chamber. It will be understood that each cylindrical shell 17 18 is provided

with the internal spray-plate and the inclined baffle and that these parts have the operative relation to the condensing-nozzle shown by the right-hand portion of Fig. 2. Below the condensing-chamber are arranged pressure-chambers 30, each of which is provided at its upper side with a perforated spray-plate or rose 31, and to these pressure-chambers is adapted to be supplied cold water, which is injected in the form of a spray by the rose 31 into the spiral passages 21, formed by the spiral flanges and the cylindrical shells in the end portions of the condensing-chamber.

The exhaust-steam from the ports *m m'* of each valve-chest is coveyed by the passages *M M'* to the spiral passages 21 of the condenser, and this exhaust-steam is caused to circulate through the spiral passages 21 around the shells 17 18, said steam being partially condensed by the influx of cold water from the pressure-chambers 30 and the rose-plates 31. The steam, the water of condensation, and the cold water from the pressure-chambers find their way into the interior of the shells 17 18 through the ports 32, which are provided in said shells at or near the inner termini of the spiral ribs, and the inflowing steam and water are directed toward the heads 19 by the inclined baffles 29, at which points the steam and water are exposed to the action of columns of cold water which are supplied directly to the cylindrical casings by branch pipes 33. The branch pipes 33 are connected with a cold-water feed-pipe 34, from which rise the two branches 33, that are situated at opposite ends of the condensing-chambers, and these branch pipes 33 have short lengths 35, which lead into the pressure-chambers 30, whereby the feed-pipe 34 is connected operatively with said pressure-chambers 30 and with the heads 19 in a way to discharge cold water under suitable pressure into the cylindrical shells 17 18 and said pressure-chambers 30. The water and spent unden-
sified steam in the cylindrical shells 17 18 are discharged under pressure through the contracted jet-orifices 26 of the condensing-nozzles 22 23, and the inflowing columns of water and unden-
sified steam are received in the condensing-chamber on opposite sides of the baffle 15, the latter serving to divide the inflowing columns of water and steam.

The cold water supplied to the condensing-chamber, as well as the water of condensation, falls by gravity into the subchamber or cavity 16, from whence the water is conveyed by an off-bearing pipe 36, while the unden-
sified steam rises in the condensing-chamber on opposite sides of the baffle 15 and passes into the off-bearing passages 37 38. (See Figs. 2 and 7.) These passages are provided in the saddle member, so as to extend from each condensing-chamber to one compression-cylinder 7 or 8, and in said passages 37 38 are provided check-valves 39, which open freely into the compression-chamber and are adapted to close automatically in a way to prevent the

steam under compression from passing backwardly through the passages into the condensing-chambers. The piston-rod 13 of the compressing-pump operates in the compressing-cylinder 7 or 8 to impart the desired reciprocation to the piston-head 14, and as this piston-head moves in one direction one of the check-valves 39 is closed, while the other check-valve is opened by the suction created by the movement of the pump-piston, so as to draw in the unden-
sified steam from the condensing-chambers 5 or 6. From each compression-cylinder 7 or 8 lead the spent steam-pipes 40 41, which extend through the smoke-box *J* and are united in a short pipe 42, the latter being extended or carried through the tube-sheet *a* and equipped with a discharge-nozzle 43, the latter being normally closed by a gravity check-valve 44. This discharge-nozzle of the spent steam-pipes lies within the steam-space of the boiler, and the spent steam which is compressed in the compression-pumps is discharged under pressure directly into the boiler, as will be understood by reference to Figs. 2 and 7.

O designates an ordinary blast-nozzle, which projects upwardly from the bottom of the smoke-box *J*, and, as is usual, lies in line with the smoke-stack *J'*. This blast-nozzle communicates with the condensing-chambers 5 6 in the members of the saddle by vertical passages 45, which are separated by an intermediate partition 46, the said passages 45 communicating with the condensing-chambers on opposite sides of the baffles 15, as shown by Fig. 4. In the blast-nozzle *O* is provided any suitable type of valve 47, shown by Fig. 2 in the form of a damper, and said valve is mounted on a rock-shaft 48, extending outside of the smoke-box *J*, said rock-shaft being provided with a crank-arm 49, to which is connected an operating-rod 50, which leads alongside of the boiler to the engineer's cab, (see Figs. 1, 3, and 4,) thus making provision for closing the valve 47 when the engine is to be used in its condensing condition. When the valve 47 is closed, the spent steam after condensation does not have sufficient pressure to open the valve 47, and is therefore required to pass through the passages 37 38 under the suction of the compression-pumps into the piston-cylinders of said pumps; but when the engine is used in its non-condensing condition and the supply of cold water is cut off to the condensers the steam is free to pass from the valve-chests *G G'* through the condensers and into the passages 45, from whence the steam passes through the blast-nozzle *O* and the smoke-box into the stack *J'*.

I will now proceed to describe the pump mechanism by which cold water is drawn from the tank in order to be forced under pressure to the condensers, and this pump mechanism also includes means for drawing the partially-heated water from the condensers and forcing the same back to the tender or other place of storage. I employ two cold-water pumps 51

4

52, which are suitably supported on a part of the running-frame C, as shown by Figs. 3, 4, and 5, and each pump has the cold-water-feed pipe 34 connected to the lower part thereof, 5 said pipe 34 being supplied by the pump 51 or 52 with cold water for conveying the same to the branches 33 35 to supply the condenser. A cold-water-supply pipe 53 is also connected with the lower portion of each pump 51 and 52, 10 and this pipe 53 is united by a flexible length of pipe or hose 54 to a part of the tender P, (see Fig. 1,) whereby cold water may be supplied to the pumps 51 52 and forced under pressure to the condensers. I also employ a pair of 15 return-pumps, indicated at 55, the same being disposed in rear of the pumps 51 52 and supported on the framework C. These pumps 55 are connected with the subchambers 16 of the condensers by the pipes 36 and said pumps 20 are furthermore connected with the tender by pipes 56 and the flexible hose 57, as shown by Figs. 1 and 5. The sets of pumps 51, 52, and 55 are operatively connected with a rocking pump-shaft 58, the latter having suitable levers 59, which are connected pivotally at 60 25 with the plunger-rods 61 of the series of water-forcing pumps, and this pump-shaft 58 is provided with a depending arm 62, to which is connected the front end of a pump-driving pitman 63, extending rearwardly from the pump 30 mechanism to a crank-pin 64 on one axle B of the locomotive. Under some circumstances I may provide this axle B with a crank, as shown by Fig. 5; but if it is desired to preserve 35 the continuity of the axle B the pump-driving pitman 63 may be actuated by an eccentric which is suitably provided on said axle B. It will be understood that the crank or eccentric of the axle operates the pitman 63 and 40 the arm 62 to rock the shaft 58, which in turn oscillates the levers 59 to actuate the groups of pumps 51 52 55, and these pumps thereafter operate to draw cold water from the tender and inject it under pressure into the condenser 45 and to draw the partially-heated water from the condenser and force the same back into the tender. The pump-shaft 58 is furthermore provided near its end portions with upstanding arms 65, to which are connected the rear 50 ends of the piston-rods 13 of the compressing-pumps 7 8, whereby the shaft 58 not only operates the groups of water-pumps, but it also drives the pistons of the compressing-pumps in order to create suction from the condensers 55 and supply steam to the compressing-pumps, the latter being operable to compress the spent steam remaining after condensation and to force the same back into the boiler under suitable pressure. 60 When the engine is used in its non-condensing form, atmospheric air should be supplied to the compressing-pump cylinders 7 8 in order to prevent the latter from drawing steam from the condensing-chambers 5 6, and to accomplish this end I provide air-pipes 66 67, which extend vertically to the

compressing-cylinders 7 8. These air-pipes 66 67 are provided at their lower ends with valves 68, having arms 69, pivoted to an operating-rod 70, and to this rod is connected 70 the lower portion of an upright lever 71, which is carried on the framework, the upper end of said lever being pivoted to a rod 72, extending rearwardly to the cab, as shown by Fig. 1.

Having thus described my invention, I 75 claim as new and desire to secure by Letters Patent—

1. A condensing-engine having a condensing-chamber in communication with the exhaust of a valve-chest, a condensing-nozzle 80 in said chamber, a tortuous circulation-passage in said chamber and arranged to conduct exhaust-steam into the nozzle, means for injecting cold water into the circulation-passage, and means for injecting water into the 85 condensing-nozzle.

2. A saddle provided with a condensing-chamber having direct connection with the exhaust of a valve-chest, condensing-nozzles disposed in facing relation within said chamber and discharging into a common exit-chamber, circulation-passages surrounding the nozzles and each arranged to conduct exhaust-steam in a tortuous path before admitting the same to one nozzle, and means for 95 injecting cold water into said passages and the nozzles.

3. In a condensing-engine, the combination of a condensing-chamber in communication with an exhaust of the engine, condensing-nozzles disposed in said chamber in facing relation, a spiral passage adjacent to each condensing-nozzle, and means for injecting cold water into said spiral passages and in the path of steam circulating therethrough. 105

4. In a condensing-engine, the combination of a condensing-chamber having communication with an exhaust of the engine, cylindrical shells supported in said condensing-chamber and forming therewith spiral circulating-passages, condensing-nozzles in communication with said shells, means for spraying cold water into said circulation-passages, and means for feeding cold water into the shells. 115

5. In a condensing-engine, the combination of a condensing-chamber, condensing-nozzles in said chamber, shells fixed within said chamber and provided with flanges arranged to form circulation-passages and with ports which establish communication between the chambers and said passages, means for spraying water into the circulation-passages, and means for feeding water into the chambers of said shells. 120

6. In a condensing-engine the combination of a condensing-chamber having communicating therewith a subchamber and pressure-chambers, condensing-nozzles having contracted orifices and disposed within said condensing-chamber, chambered shells having 125 external flanges forming circulation-passages which communicate with the chambers of said

shells, spray-plates covering the pressure-chambers and arranged to discharge sprays of water into the circulation-passages, and means for forcing currents of water into the 5 chambers of said shells.

7. In a condensing-engine, the combination of a condensing-chamber, shells secured therein and forming circulating-passages therewith, condensing-nozzles within said chamber and communicating with said shells, means for injecting water into the passages in the shells, and baffle-plates within the shells and inclined relatively to the water-inlets thereto.

15 8. In a condensing-engine, the combination of a condensing-chamber having condensing-nozzles disposed in facing relation, a return water-pipe connected with the condensing-chamber between said nozzles, a feed-water pipe connected to the condensing-chamber to supply water to said nozzles, and independent pumps to which said feed and return pipes are individually connected.

25 9. In a condensing-engine, the combination of a condensing-chamber having condensing-nozzles, a pump-shaft, independent forcing and return pumps operatively connected with said shaft, a feed-pipe connected to one pump for supplying water to the condensing-nozzles, 30 and a return-pipe connected to the other pump and to the condensing-chamber at a point between said nozzles.

35 10. In a condensing-engine, the combination of a condensing-chamber having condensing-nozzles, a pump-shaft provided with an arm, a pitman connected with said arm, independent forcing and return pumps operatively connected with said pump-shaft to be actuated thereby, feed-pipes connected to the forcing- 40 pump and the condensing-chamber, and a return-pipe connected to the return-pump and to the condensing-chamber at a point between the nozzles therein.

45 11. In a condensing-engine, the combination with a boiler, of a condensing-chamber, supply and return water pumps connected with said condensing-chamber, an independent spent-steam compression-pump operatively connected with said condensing-chamber to receive 50 spent steam subsequent to condensation thereof, and means connecting said compressing-pump with said boiler to return spent steam under pressure to the boiler.

55 12. In a condensing-engine, the combination of a condensing-chamber having nozzles and means for spraying water therein, means for conveying exhaust-steam to said condensing-chamber in the path of the water-sprays, a compressing-pump, valved connections between said compressing-pump and said condensing-chamber, and means for conveying compressed steam from said pump to a suitable place of storage.

65 13. In a condensing-engine, the combination with a boiler having a smoke-box, of a condensing-chamber having communication with

the exhaust of said engine, nozzles within said condensing-chamber, a baffle between the nozzles, means for injecting water into the condensing-chamber and its nozzles, a 70 compressing-pump, valved steam-passages between said pump and the condensing-chamber to receive spent steam at a point between said nozzles, and connections between the compressing-pump and steam-space of the 75 boiler.

14. In a condensing-engine, the combination of a condensing-chamber having communication with the exhaust of an engine, nozzles within said condensing-chamber, means for 80 supplying water to said nozzles, means for conveying water from the condensing-chamber at a point between the nozzles, a baffle situated within said condensing-chamber between the nozzles, a compressing-pump, a 85 boiler, valved connections between the compressing-pump and the condensing-chamber, said connections opening into the condensing-chamber at points between the nozzles and the intermediate baffle, and valved connections leading from the compressing-pump to the steam-space of the boiler. 90

15. In a condensing-engine, the combination of a condensing-chamber having communication with the exhaust of an engine, a boiler, 95 a blast-nozzle communicating with said condensing-chamber and having a controlling-valve, nozzles within the condensing-chamber, means for injecting water into said chamber, means for conveying water from 100 the chamber, a compressing-pump, valved connections from the condensing-chamber to said compressing-pump, and other valved connections leading from the compressing-pump to the boiler. 105

16. In a condensing-engine, the combination of a condensing-chamber having communication with the exhaust of an engine, a boiler, a compressing-pump operatively connected with said condensing-chamber and said 110 boiler, forcing and return pumps connected with the condensing-chamber to supply water thereto and to draw water therefrom, and a single pump-operating mechanism connected with the compressing-pump, the forcing- 115 pump and the return-pump.

17. In a condensing-engine, the combination of a condensing-chamber having communication with the exhaust of an engine, nozzles within said condensing-chamber, means for 120 supplying water to said chamber and drawing it therefrom, a compressing-pump having valved communication with the condensing-chamber, and air-cocks connected with the compressing-pump and having means for 125 controlling the same at will.

18. In a condensing-engine, the combination with valve-chests, of condensing-chambers connected individually with the exhaust of said valve-chests, nozzles within said condensing-chambers, forcing and return pumps connected with the condensing-chambers to 130

supply water to the nozzles thereof and to draw water from points between said nozzles, a boiler and compressing-pumps having valved connections with the condensing-chambers and with said boiler, and a pump-shaft operatively connected with said series of pumps.

In testimony whereof I have signed my name to this specification in the presence of two subscribing witnesses.
